UNITED STATES PATENT OFFICE

HERMAN J. KONANZ, OF GRANTWOOD, NEW JERSEY

COLLAPSSIBLE TUBE

Application filed December 1, 1931. Serial No. 578,262.

This invention is a collapsible tube adapted for use for the packaging of creams, such as tooth paste, shaving creams, etc., and the invention is directed more particularly to the provision of a satisfactory enclosure for such a tube.

Collapsible tubes have long been used but the closures heretofore provided have not been satisfactory. The most common type of closure is that wherein a threaded cap is screwed upon the threaded neck of the tube, but experience has shown that the majority of creams used in tubes harden or solidify in the threads and make difficult the removal or replacement of the cap. As a result, it has been quite common in prior constructions to use the cap for a while and to thereupon discard the cap so the tube is left without a closure. When thus used, the creams harden within the neck of the tube and form an effective plug or stopper which effectually precludes the discharge of further paste unless a match, toothpick or some similar article is used to puncture or force out the stopper thus formed.

Devices have heretofore been suggested which do not require the threading of the cap on the neck of the tube, but these devices have in the main been open to the general objection that the operation of the cap on the neck of the tube produces a smudging of the paste in the clearance space between the parts, and as a result of this smudging a thin layer of paste is accumulated in this clearance space. This layer of paste solidifies, jams the cap and precludes its ready removal.

The object of the present invention is to eliminate the foregoing disadvantages and others and to provide an economical and thoroughly efficient closure for a tube of the character specified.

A further important advantage inherent in the structure of the present invention is its simplicity and economy of manufacture. An important factor in this connection resides in the fact that the tube, as well as the cap may be separately and independently made in complete form and the parts there-

after assembled without requiring a further operation in the formation of the parts.

Speaking generally, the invention consists in making the neck of the tube in the form of a substantially cylindrical dome, the outer surface of which is cylindrical and the neck preferably being provided with a flat top. At the base of the neck is formed a seat and above and adjacent the seat, the neck is formed in its lateral wall with an outlet opening for the paste. The cap fits over the neck with a close sliding fit and there is formed between the cap and the neck a bayonet joint connection, the male member of which is formed on and integral with the cap. The female joint connection has a branch slot which permits the parts to be assembled after complete formation by providing means of entry of the pin of the joint into the bayonet slot of the neck.

This assembly is expeditiously accomplished and is so constituted, as hereinafter described, that the cap is, to all intents and purposes, locked against removal from the tube, while serving as an efficient seal and closure.

Features of the invention, other than those specified, will be apparent from the herein-after detailed description and drawing, when read in conjunction with the appended claims.

The accompanying drawing illustrates one practical embodiment of the invention, but the construction therein shown is to be understood as illustrative, only, and not as defining the limits of the invention.

Figure 1 is a perspective view of a collapsible tube embodying the present invention, showing the cap detached.

Figures 2 and 3 are central sections through the tube and cap, the former of which figures show the cap in sealing position and the latter of which shows the cap in unsealing position.

In the drawing, the body of the tube is designated 1 and upon this body is formed a neck 2 having a cylindrical exterior and a flat top 3. At one side of the neck near the base thereof is an outlet opening 4 and at the base of the neck is formed an annular seat 5.

The cap 6 has a cylindrical interior proportioned to have a close sliding fit with the exterior of the neck and said cap is of a depth to fit over the neck with its lower edge 7 cooperating with the seat 5 when the cap is in closed position.

In the exterior face of the neck is formed a bayonet slot or channel designated generally by the reference character 8. This slot has 10 an upright portion 9 and a circumferential portion 10, the latter of which is inclined downwardly as shown in Figure 1. The upper end of the upright portion 9 is closed, i. e., the slot terminates short of the top of the 15 neck and about midway of this upright portion is an intersecting branch slot 11, which extends circumferentially for a distance and thence upwardly as at 12 to the top of the neck. This branch slot I call the entrance 20 slot. It is provided in order to permit the pin 14 of the joint to be formed integral with and permanently secured to the cap 6, so as to project interiorly of the cap. The parts are so arranged that the cap may be made complete 25 with the pin 14 attached and the neck of the tube may be made complete in the formation of molding the tube and after these parts have been completely formed independently of one another, they may be thereupon assembled 30 without further addition of any parts.

In order to accomplish this result, the cap is brought into a position to cause the pin 14 to enter the upright part 12 of the entrance slot and then by pressing down the cap the pin 35 is brought opposite the part 11 of this slot, so that rotation of the cap in a counterclockwise direction will cause the pin to traverse the portion 11 of the entrance slot and enter into the bayonet slot proper. This completes the assembly 40 operation. To move the cap in a sealing position, it is forced downwardly until the pin is juxtaposed with the portion 10 of the bayonet slot whereupon rotation in a clockwise direction will cause the pin 14 to enter this portion of the slot, the downward 45 inclination of which will force the lower edge of the cap firmly to the seat 5. To open the cap, the cap is first turned in a counterclockwise direction and then lifted until the pin 50 14 reaches the top of the upright portion 9 of the bayonet slot, whereupon the parts will appear as shown in Fig. 3, from which it will be seen that the opening 4 is uncovered and that paste may be exuded from the tube. 55 After the desired quantity of paste has been forced out by squeezing the tube, the cap is pressed down and its lower edge acts as a knife blade to shear off the paste cleanly and without smudging and to form a closure as 60 shown in Fig. 2.

It will be noted that the upper end of the slot portion 9 is curved slightly in the direction of the branch slot. Thus in order to move the cap from the position of Figure 3 65 to the position of Figure 2, it is first necessary

to slightly rotate the cap in a counterclockwise direction. This causes the pin during the downward movement of the cap to hug the right hand side of the slot portion 9, so that there is no tendency of the pin to enter 70 the part 11 of the branch slot. As the natural tendency in raising the cap is to turn it to the left, the pin will not engage with the branch slot during its opening movement.

Experience with a closure of the character 75 described has shown that persons using the tube are not even aware of the presence of the branch slot because the formation of the bayonet slot is such that the natural operations of the parts preclude interference by 80 the branch slot and as this slot is concealed at all times by the cap, the user is not even aware of its presence. It does not function during the useful life of the tube and is simply an assembly means to economize and expedite 85 assembly operations during the course of manufacture. Yet it efficiently solves an important manufacturing problem of getting the pin of the bayonet joint into the bayonet slot without a separate and independent 90 operation subsequent to the initial formation of the parts and at the same time it provides a structure which to all intents and purposes has a non-removable cap.

Having thus fully described the invention, 95 what I claim as new and desire to secure by Letters Patent is:

1. A collapsible tube comprising a body provided at one end with a neck having an opening in its side wall and which neck has a 100 cylindrical outer surface at the base of which is provided an annular seat and in which outer surface is formed a bayonet channel having an upstanding portion terminating short of the upper end of the neck and at the 105 lower end of which upstanding portion is formed a circumferential downwardly inclined bayonet channel portion, a cap provided with a cylindrical interior to have a sliding fit with the neck, and a projection formed 110 on the interior of the cap, there being formed in the cylindrical surface of the neck a branch channel extending from the upper end of the neck to the upright portion of the bayonet channel, whereby the projection on 115 the cap may be passed through the branch channel into the bayonet channel during the assembly of the cap on the neck, the lower edge of the cap being beveled to cooperate with the seat at the base of the neck.

2. A collapsible tube comprising a body provided at one end with a neck having an opening in its side wall and which neck has a cylindrical outer surface and in which outer surface is formed a bayonet channel having 120 an upstanding portion terminating short of the upper end of the neck and at the lower end of which upstanding portion is formed a circumferential downwardly inclined bayonet channel portion, a cap provided with a 125

cylindrical interior to have a sliding fit with the neck, and a projection formed on the interior of the cap, there being formed in the cylindrical surface of the neck a branch channel extending from the upper end of the neck to the upright portion of the bayonet channel, whereby the projection on the cap may be passed through the branch channel into the bayonet channel during the assembly of the cap on the neck, that part of the upright portion of the bayonet channel above the entrance of the branch channel being curved or inclined in the direction of said branch channel.

15. In testimony whereof, I have signed the foregoing specification.
